her Attorney.

UNITED STATES PATENT OFFICE.

ELIZABETH MILES, OF EVANSTON, ILLINOIS.

ADJUSTABLE BRASSIÈRE.

1,195,835.

Specification of Letters Patent. Patented Aug. 22, 1916.

Application filed April 30, 1915. Serial No. 24,941.

To all whom it may concern:

Be it known that I, ELIZABETH MILES, a citizen of the United States, and a resident of the city of Evanston, county of Cook, 5 and State of Illinois, have invented a certain new and useful Adjustable Brassière, of which the following is a specification.

My invention relates to a certain new and useful adjustable brassière, and has for its 10 object the provision of a construction of this character especially adapted for use during maternity.

The invention consists in the combinations and arrangements of parts hereinafter 15 described and claimed.

The invention will be best understood by reference to the accompanying drawing forming a part of this specification, and in which,

20 Figure 1 is a front perspective view of a garment embodying my invention and shown in position of use, Fig. 2, a perspective view of the rear of said garment shown in position of use, and Fig. 3, a plan view of the 25 garment detached and spread out flat.

The preferred form of construction, as 30 illustrated in the drawing, comprises a garment made up in three parts, namely a rear portion 4 and two front portions 5, said portions being secured together by lines of lacing 6 positioned under the arm holes of the garment. The sides of the arm holes of 35 the garment are extended somewhat and are provided with a plurality of buttons 7 and button holes 8 by means of which the garment may be adjustably secured over the shoulders. The upper front portions of the garment portions 5 are extended at 9 to overlap at the front to cover the bust and the 40 lower portions thereof are still further extended at 10 and securing straps 11 are secured to these extended portions 10. Slits 12 are provided in the lower side portions of the garment and buckles 13 are arranged 45 adjacent said slits to receive and secure the ends of straps 11. Suitable stiffening "bones" or "steels" 14 may be arranged in the garment, as desired, the same being, however, preferably of comparatively light and 50 flexible material.

The garment is placed on the wearer in the usual manner by inserting the arms

through the arm holes formed by buttoning the button holes over one or the other of the buttons 7. The front portions of the garment are then overlapped, as indicated in Fig. 1, the inner strap 11 being passed outwardly through the corresponding slit 12 and secured to the corresponding buckle 13. The other strap 11 is merely brought around 60 the waist and secured to the corresponding buckle 13, the two slits 12 being provided for convenience in case it should be found more convenient to overlap one side of the garment rather than the other. By this arrangement, the garment may be readily adjusted to changes and variations in the form 65 of the wearer, and owing to the peculiar shape of the front portions of the garment and particularly to the extensions 10 at the 70 lower portion thereof, a downwardly and inwardly inclined tension is imparted to these portions of the garment by the straps thus adequately supporting the bust of the wearer.

While I have illustrated and described the 75 preferred form of construction for carrying my invention into effect, this is capable of variation and modification without departing from the spirit of the invention. I, therefore, do not wish to be limited to the 80 precise details of construction set forth, but desire to avail myself of such variations and modifications as come within the scope 85 of the appended claims.

Having described my invention what I 85 claim as new and desire to secure by Letters Patent is:

1. A garment of the class described, laced under the arms, having adjustable arm holes, open at the front and overlapped to 90 cover the bust, the lower portions of said overlapped portions being extended; straps secured to said extended portions; and buckles on said garment for said straps, there being slits in the lower side portions 95 of said garment to permit the passage of said straps, substantially as described.

2. A garment of the class described comprising a rear portion and two front portions, having arm holes formed at the junctions between said portions and said portions being adjustably secured together under the arm holes by lacings; extended sides to said arm holes, said sides being provided

with a plurality of button holes and buttons, the upper front portions of the front portions of the garment being extended sufficiently to overlap to cover the bust and the 5 lower front portions being still further extended; securing straps secured to said lower extensions, there being slits in the lower side portions of the garment arranged to permit the passage of said straps; and

buckles secured to said garment at the rear 10 of said slits, substantially as described.

In testimony whereof I have signed my name to this specification in the presence of two subscribing witnesses.

ELIZABETH MILES.
